COMBINED MIRROR AND LIPSTICK HOLDER

Ethel Hubbard, 240K Old Country Road, Hicksville, N.Y.

Filed June 2, 1960, Ser. No. 60,825

Term of patent 7 years

(Cl. D86—10)

Fig. 1 is a front perspective view of a combined mirror and lipstick holder showing my new design, the broken line showing of a lipstick being for illustrative purposes only:

Fig. 2 is a front elevational view thereof;

Fig. 3 is a side elevational view;

Fig. 4 is a rear elevational view; and

Fig. 5 is a side elevational view thereof as it appears with the easel in open position.

I claim:

The ornamental design for a combined mirror and lipstick holder, as shown and described.
